UNITED STATES PATENT OFFICE.

JOHN YOUDS, OF CHISELHURST, ENGLAND.

GOLF-CLUB.

No. 922,444.

Specification of Letters Patent.

Patented May 18, 1909.

Application filed January 27, 1908. Serial No. 412,884.

To all whom it may concern:

Be it known that I, JOHN YOUDS, a subject of the King of Great Britain and Ireland, of the Golf Club, Chiselhurst, in the county of 5 Kent, England, have invented new and useful Improvements in Golf-Clubs, of which the following is a specification.

My invention has for its object to provide a golf club with a striking face better adapted for certain requirements of the game of golf than are the striking faces of the characters hitherto used.

I have found that if the striking faces of golf clubs (such as "putters" and "approach irons" more especially) be made of lead, the effect on the ball (and especially on a ball with a rubber core) is better and more certain in the required effect, especially in "approaching" and "putting", than is the case with striking faces of the characters hitherto used. I therefore apply to clubs with steel, aluminium, iron, wood, or other, heads, a striking face of lead which may be fixed to the head in any convenient way, such, for example, as by being cast, or otherwise held securely and permanently, in a recess in the head, or by being screwed, or otherwise fixed, to the head, so as to form a striking face which constitutes practically an immovable and fixed part of the head of the club. When the lead is applied by casting, the club head may be formed with undercut parts into which part of the lead enters in casting, so as to permanently fix the lead to the head, and when screws, or other fastenings, are used, the head and lead facing may be formed with engaging parts as for example beveled edges to give a firm fixture of the lead to the head, as shown in Figures 6 and 7.

The accompanying drawing represents golf clubs made in accordance with my invention, in which the lead striking face is applied by casting, but I do not limit myself 45 to the application of the lead by casting.

Fig. 1 is an elevation, Fig. 2 a transverse section, and Fig. 4 a plan, of the head and part of the stick of a "putter", Figs. 1 and 3 showing the head prepared for receiving the lead striking face, and Fig. 2 showing the lead striking face applied. Fig. 5 is an elevation, and Fig. 6 is a transverse

section, of an "approach iron" with a lead striking face applied thereto; Fig. 6 is an elevation; and Fig. 7 is a transverse section of 55 the same with the lead applied thereto in a different manner.

In the head 1 I make a recess 2 which is undercut at the ends 3. In the head, at the back of this recess, I make openings 4 which are preferably undercut, or, better still, screw-threaded, as then they can be readily formed by a screw-tap. The head is then placed in a suitable holder, or mold, and molten lead is poured in so that it fills the 65 openings 4 and recess 2 and on solidifying is firmly and securely held therein and, after any necessary trimming up, constitutes the striking face 5. The foregoing description applies to both the clubs shown in the drawing. As the "putter" (Figs. 1, 2 and 3) is used on grass, the lead can extend down to the lower edge, but as the "approach iron" (Figs. 4 and 5) is used on ground which may be hard and rough, it is preferable not to 70 make the recess for the lead right through to the underside, but to leave at bottom a ridge 7 of the original hard metal. In any case, an edge of the original material of the club head may be left either at top, or bottom, of the recess, or at both the top (Figs. 6 and 7) and bottom, to protect the lead 80 from injury.

Having now particularly described and ascertained the nature of my said invention 85 and in what manner the same is to be performed, I declare that what I claim is:—

1. A golf club of the class specified having a head and a striking face of lead secured thereto.

2. A golf club of the class specified having a head and a striking face of soft metal secured thereto.

3. A golf club of the class specified having a hard metal head and a striking face of soft 95 metal secured thereto.

In testimony whereof I have signed my name to this specification in the presence of two subscribing witnesses.

JOHN YOUDS.
